UNITED STATES PATENT OFFICE.

JOHN M. WELCH, OF BROOKLYN, NEW YORK, ASSIGNOR TO FEDERATED ENGINEERS DEVELOPMENT CORPORATION, OF JERSEY CITY, NEW JERSEY, A CORPORATION OF DELAWARE.

CIGARETTE HOLDER.

Application filed October 20, 1922. Serial No. 595,801.

To all whom it may concern:

Be it known that I, JOHN M. WELCH, a citizen of Canada, and a resident of New York city, borough of Brooklyn, in the county of Kings and State of New York, have invented a new and Improved Cigarette Holder, of which the following is a full, clear, and exact description.

This invention relates to improvements in cigarette holders of the general character disclosed in my copending applications, Serial Nos. 518,711 and 558,356, filed November 9, 1921, and May 4, 1922, respectively, one purpose of the present invention being to improve the butt ejecting mechanism of the holder whereby to render the same more sanitary and less expensive to manufacture and assemble.

It is to be understood that the ejector mechanism works on the same principle as that disclosed in my co-pending applications; that is, the ejector member is adapted to be actuated by shaking the holder longitudinally of its length.

With the object of facilitating the cleaning of the holder and with other objects in view, the invention consists in certain novel features of construction and combinations and arrangements of parts, as will be more fully hereinafter described and pointed out in the claims.

The accompanying drawing is a view in longitudinal section through my improved holder.

Referring with particularity to the drawing, I have used the reference numeral 1 to designate the body of the holder which is externally tapered and flanged adjacent one end so that it may be conveniently gripped by the teeth of a user.

An enlarged bore or chamber 2 is provided in the cigarette receiving end of the body, said bore communicating with and forming a continuation of a relatively small smoke passage 3 adjacent the mouthpiece end of the body. The walls of the small bore are screw-threaded as at 4 adjacent their point of communication with chamber 2. A cylindrical guiding and retaining member 5 externally threaded at one end to fit the screw-threaded portion 4 of the smoke passage provides mounting for a cylindrical ejector 6 loosely fitting and telescoping thereon. Engaging lips 7, 8 at the inner end 55 of the ejector 6 and outer end of the guide

5 limit the forward movement of the ejector while the rear wall of chamber 2 checks the rearward movement thereof.

The ejector 6 is of course sufficiently heavy to slide forwardly and eject the butt 10 of a cigarette as the holder is shaken longitudinally of its length.

The construction above described permits the holder to be readily cleaned with an ordinary pipe cleaner. There is little tendency 15 for the oils in the smoke to condense on the exterior of the ejector or guide member and interfere with the free sliding of the ejector since the smoke passes through rather than around these members. The appearance of 20 the holder is not affected in any way by the provision of the ejector since the ejecting mechanism is entirely concealed within the bore of the holder.

I have called the device a cigarette holder 73 because it is most commonly used as such, but the invention of course contemplates similar constructions for use as cigar holders. The preferred embodiment only of the invention is herein illustrated. It will be evident that 78 various changes and alterations might be made in the general form and arrangement of the parts described without departing from the invention and hence, I do not wish to limit myself to the precise details set 83 forth, but shall consider myself at liberty 88 to make such slight changes and alterations as fairly fall within the spirit and scope of the appended claims.

I claim:

1. A holder of the class described having a smoke passage extending therethrough, a cylinder member fixed in said smoke passage, and a cylindrical ejector telescoping upon said member.

2. A holder of the character described comprising a tubular member formed with an enlarged chamber adapted to receive a cigar or cigarette, an ejector freely slidable in the chamber, and guiding means for guiding said ejector spaced from the walls of the chamber.

3. In a holder of the character described having a cigarette or cigar receiving chamber therein, an ejector freely slidable in the chamber, and guiding means for said ejector spaced from the walls of the chamber, said guiding means comprising a hollow tube upon which the ejector slides.

4. In a holder of the character described

- having a cigarette or cigar receiving chamber therein, an ejector freely slidable in the chamber, and guiding means for said ejector spaced from the walls of the chamber, 5 said guiding means comprising a hollow tube upon which the ejector slides and inter-engaging stop means on the tube and ejector to limit the sliding movement of the ejector.
- 10 5. In a holder of the character stated having a smoke passage extending therethrough and having a cigarette receiving chamber in one end thereof with which said passage communicates, a tubular guide member 15 screwed into the smoke passage, an ejector mounted to telescope on the guide member, and means on the guide member for limiting the movement of the ejector in one direction.
6. In a holder of the character stated hav-
- ing a smoke passage extending therethrough and having a cigarette receiving chamber in one end thereof with which said passage communicates, a tubular guide member 20 screwed into the smoke passage, an ejector mounted to telescope on the guide member, and means on the guide member for limiting the movement of the ejector in one direction, 25 said guide member being engageable with the rear wall of the cigarette receiving chamber to limit its movement in the other direction. 30
7. A holder of the class described having a smoke passage extending therethrough, ejector retaining means fixed in the smoke passage, and an ejector freely slidable in the smoke passage and telescopically mounted 35 upon said retaining means.

JOHN M. WELCH,
